(57) **CLAIM**

The ornamental design for a tank transport container rotating jig, as shown and described.

DESCRIPTION

FIG. 1 is a left perspective view of a tank transport container rotating jig, showing our new design;
FIG. 2 is a right perspective view thereof;
FIG. 3 is a front orthogonal view thereof;
FIG. 4 is a front orthogonal view of a left portion thereof shown in FIG. 1;

FIG. 5 is a front orthogonal view of a right portion thereof shown in FIG. 1;

FIG. 6 is a rear orthogonal view thereof;

FIG. 7 is a rear orthogonal view of the left portion thereof shown in FIG. 1;

FIG. 8 is a rear orthogonal view of the right portion thereof shown in FIG. 1;

FIG. 9 is a left orthogonal view thereof;

FIG. 10 is a left orthogonal view of the left portion thereof shown in FIG. 1;

FIG. 11 is a left orthogonal view a right portion thereof shown in FIG. 1;

FIG. 12 is a right orthogonal view thereof;

FIG. 13 is a right orthogonal view of the left portion thereof shown in FIG. 1;

FIG. 14 is a right orthogonal view the right portion thereof shown in FIG. 1;

FIG. 15 is a top orthogonal view thereof;

FIG. 16 is a top orthogonal view of the left portion thereof shown in FIG. 1;

(Continued)

FIG. 17 is a top orthogonal view of the right portion thereof shown in FIG. 1;

FIG. 18 is a bottom orthogonal view thereof;

FIG. 19 is a bottom orthogonal view of the left portion thereof shown in FIG. 1; and,

FIG. 20 is a bottom orthogonal view of the right portion thereof shown in FIG. 1.
